UNITED STATES PATENT OFFICE.

ERNST F. W. ALEXANDERSON, OF SCHENECTADY, NEW YORK, ASSIGNOR TO GENERAL ELECTRIC COMPANY, OF NEW YORK, N. Y.

ELECTRON-DISCHARGE DEVICE.

Application filed September 28, 1920, Serial No. 413,337. Renewed March 12, 1923.

To all whom it may concern:

Be it known that I, ERNST F. W. ALEXANDERSON, a citizen of the United States, residing at Schenectady, county of Schenectady, State of New York, have invented certain new and useful Improvements in Electron-Discharge Devices, of which the following is a specification.

The present invention comprises a novel 10 electron discharge device which is particularly adapted to the controlling and amplifying of electrical currents.

Heretofore electron discharge devices have been constructed in which the transmitted current was subject to the control 15 of a variable magnetic field. In these devices the cathode was axially arranged within the anode, preferably being substantially equidistant from the anode at all points 20 along its length.

I have discovered that an even more sensitive device can be constructed by locating the anode centrally with respect to the cathode, and preferably spacing the electrodes 25 symmetrically.

I have illustrated diagrammatically in Fig. 1 a form of apparatus embodying my invention; Fig. 2 is a diagram illustrating an electrical characteristic of my device, 30 and Figs. 3^a, 3^b and 3^c illustrate visually electron flow under various conditions as an aid to explain my invention.

The device shown in Fig. 1 is adapted for use as an amplifier for weak electrical currents, for example, radio signals. It comprises an elongated glass envelope 1 containing a centrally located elongated or rod-like anode 17 and a helical cathode 2 symmetrically surrounding the anode. The cathode 2 is preferably although not necessarily equidistant from the anode 17 at all points along its length and in general I prefer to arrange the electrodes in devices embodying my invention in circular symmetry with respect to each other.

The cathode 2 is adapted to emit electrons independently of the passage of current across the space between the electrodes; for example, in the case illustrated in the figure the cathode consists of refractory material, preferably tungsten, connected by conductors 3, 4, to a suitable source of electric energy represented by an electric battery 5. A regulable resistance 6 is provided to control the heating current. The

anode 17 may also consist of tungsten and various other metals may also be used. The space within the envelope is evacuated and the parts of the device are deprived of gas to such an extent that the electron discharge can occur therein without material gas ionization. A slight amount of gas ionization will do no harm, but it should not be so high as to make the electrons uncontrollable by a magnetic field. Some 65 suitable means for generating a variable magnetic field is provided, as, for example, a coil 7 which has been diagrammatically shown adjacent to the discharge tube, but which, as in devices of this type, will ordinarily surround the tube. This coil 7 is connected to the source of weak variable current which is to be amplified, as represented in this case by the conductors 8, 9.

There is also provided some means for 75 generating a polarizing electric field, as represented by coils 10 and 11, connected in series to a source of direct current such as a battery 12 in circuit with a variable resistance 13. In circuit with the electrodes 80 2 and 17 are included a suitable source of direct current as represented by the battery 14 and a suitable indicating device such as a telephone receiver 15.

When no exterior magnetic field is applied to an electron discharge device having an anode centrally located with respect to the cathode the electrons in general tend to move in direct paths from the cathode to the anode, as shown in Fig. 3^a. When a 90 magnetic field is generated substantially parallel to the cathode, the electrons are deflected out of a direct path. With a central location of the cathode in prior devices the path of the electrons tend to become curved 95 as shown in Fig. 3^c. When the magnetic field is increased sufficiently the electrons eventually travel in a long spiral path about the cathode on their way to the anode and finally when the field strength is increased 100 sufficiently electrons will fail to reach the anode by reason of this deflection.

In a device having a centrally located anode the electrons flowing inwardly from the surrounding cathode to the anode when 105 deflected by a magnetic field as shown in Fig. 3^b, are caused to travel in a general direction tangentially to the anode and tend to form orbits about the anode. As the centrifugal force of the mass of electrons 110

works in the same direction as the magnetic field in a device having a centrally located anode, such a device is much more sensitive to variations of the magnetic field than a device having the cathode located within the anode. In the latter case the magnetic field must be strong enough to overcome the centrifugal force of the electrons in their circular path. The relation between the magnetic field tending to deflect the electrons and the current transmitted by the device is indicated by the diagram constituting Fig. 2, the values of the magnetic field being plotted as abscissæ and the corresponding field values as ordinates for a given cathode temperature. As the strength of the magnetic field is increased from zero the current remains substantially constant until the magnetic field reaches a value represented as *oa* on the abscissæ. A further increase of field strength causes a rapid reduction of current until at a field strength of *ob* current has fallen substantially to zero.

The magnetic field necessary to produce a decrease in current, in other words, the value *oa* will be less in a device embodying my invention than in devices heretofore constructed having a centrally located cathode. In practice the strength of the polarizing magnetic field is adjusted at some value between *oa* and *ob*. Consequently when the variable magnetic field of the coil 7 is superimposed upon the polarizing field an increase or decrease of conductivity of the device occurs. For example when the variable magnetic field produced by the coil 7 tends to assist the polarizing field generated by the coils 10 and 11, the current in the circuit 16 tends to decrease, and conversely, when the magnetic field of the coil opposes the polarizing field the current in the circuit 16 increases. Therefore, a variable current in the circuit 8, 9 produces a corresponding amplified variable current in the circuit 16 which can be used in any desired manner, as in a telephone receiver 15.

What I claim as new and desire to secure by Letters Patent of the United States, is,—

1. In combination, an electron discharge device adapted to operate independently of gas ionization comprising the combination of an anode, an electron-emitting cathode arranged about said anode and magnetic means arranged to oppose the passage of electrons from said cathode to said anode.
2. In combination, an electron discharge device comprising an evacuated envelope, an electron-emitting cathode and an anode inclosed by said cathode and having a major

axis extending in the direction of the major axis of said cathode and means for producing a magnetic field parallel to the axis of symmetry of said electrodes for controlling the flow of electrons from said cathode to said anode. 65

3. An electron discharge device comprising the combination of electrodes contained in an evacuated space, the cathode comprising a coiled conductor, the anode being located substantially centrally within said coiled conductor, and means for generating a magnetic field substantially parallel to the axis of said cathode. 70

4. An electron discharge device comprising the combination of an elongated anode, a helical cathode symmetrically spaced about said anode, means for heating said cathode, an enclosing evacuated envelope 80 and magnetic means for controlling an electrical discharge between said electrodes.

5. An electron discharge apparatus comprising the combination of an elongated electrode, a helical electrode spaced about 85 the same, means for conducting an electric current through said helix, a sealed evacuated envelope enclosing said electrodes, a load circuit connected to said electrodes, and a magnetic winding located to generate a 90 magnetic field substantially parallel to the axis of said helix.

6. An electron discharge device comprising in combination an evacuated envelope, an elongated anode, a filamentary cathode 95 symmetrically spaced about said anode, and means for generating a magnetic field substantially parallel to the axis of said cathode.

7. An electron discharge device comprising in combination an evacuated envelope, an elongated anode, a helically coiled cathode symmetrically arranged about said anode, means for heating said cathode to a temperature sufficiently high to emit electrons, magnetic means for producing a field which will deflect electrons out of a direct path between said electrodes, means for varying said field, and a load circuit connected to said electrodes. 100

8. An electron discharge apparatus comprising the combination of an anode, an electron-emitting cathode arranged about said anode, an enclosing evacuated envelope, an output circuit connected thereto, magnetic means for generating a field opposing the passage of electrons from said cathode to said anode and input means for varying said field. 105

In witness whereof, I have hereunto set 115 my hand this 27th day of September, 1920.

ERNST F. W. ALEXANDERSON.
